UNITED STATES PATENT OFFICE.

HERMAN A. DAVENPORT, OF BROCKTON, MASSACHUSETTS, ASSIGNOR TO UNITED SHOE MACHINERY COMPANY, OF PATERSON, NEW JERSEY, A CORPORATION OF NEW JERSEY.

SOLE-PRESSING FORM.

1,174,397.

Specification of Letters Patent.

Patented Mar. 7, 1916.

Application filed June 11, 1914. Serial No. 844,433.

To all whom it may concern:

Be it known that I, HERMAN A. DAVENPORT, a citizen of the United States, residing at Brockton, in the county of Plymouth and State of Massachusetts, have invented 5 certain new and useful Improvements in Sole-Pressing Forms; and I do hereby declare the following to be a full, clear, and exact description of the invention, such as 10 will enable others skilled in the art to which it appertains to make and use the same.

The present invention relates to machines for shaping shoe soles and more particularly to the pressing forms employed in 15 connection with machines of this type which shape the outsole to enable it to be firmly united to a lasted shoe.

The object of the present invention is to provide an improved pressing form which 20 shapes the outsole preliminary to the permanent securing of the sole to a lasted shoe to enable the outsole to be securely united to the lasted shoe.

With this object in view a feature of the 25 invention consists in the provision of a pressing form having a central pressing member, an outer pressing member surrounding the central member and arranged to yield with relation to the central member 30 when pressure is applied to the sole to form an indentation in that portion of the sole engaged by the central member.

Further features of the invention consist 35 in certain novel features of construction, combinations and arrangements of parts hereinafter described and claimed, the advantages of which will be obvious to those skilled in the art from the following description.

40 In the accompanying drawings illustrating the preferred form of the invention; Figure 1 represents a sectional view of a portion of a pressing form in its normal position; Fig. 2 is a view similar to Fig. 1 45 showing the form with the shoe located thereon under pressure; Fig. 3 is a view of the heel seat of an outsole representing the indentation formed by the plug; and Fig. 4 is an elevation partly in section of the plug.

50 In order to firmly secure an outsole to a lasted shoe it is desirable under certain conditions that a portion of the sole intermediate the margins be depressed in order that this portion of the sole shall engage and be

united with the insole. The importance of 55 this feature can be readily appreciated when it is understood that the upper of a lasted shoe forms an upstanding projection extending around the margin of the shoe and as the outsole is laid over this projection a 60 hollow is left in the interior of the shoe which must be filled. This feature may be also advantageously employed in shoes where no insole is used, but in which the upper is secured directly to a single sole. 65

In the illustrated embodiment of the invention an indentation is formed in the central portion of the heel seat of the sole, thus forcing this portion of the sole into contact with the insole to firmly unite the two at 70 this point. In existing methods of manufacture it is customary to temporarily secure this portion of the outsole in place by a fastening which is driven through the outsole and insole into the last and with the 75 present improved construction the employment of this temporary fastening is dispensed with. The illustrated embodiment of the invention is shown in connection with a pressing form of the type disclosed in the 80 patent to Davenport, No. 942,133, December 7, 1909. This pressing form consists of a rubber pad 1 supported upon a series of pad blocks 3, which in turn are supported upon mechanism to equalize the pressure 85 exerted over the entire shoe sole.

As illustrated clearly in Fig. 2 of the drawings, the pressing form is arranged to operate upon a welt shoe having an insole 5, a shank stiffener 6, a counter-portion 7 90 and an outsole 8. In the present invention the outer sole is pressed into engagement with the insole by a plug indicated at 10 which is seated in a recess 12 formed in the pad block, and extends upwardly through a 95 slot formed in the rubber pad 1. It will be noted from an inspection of Fig. 1 that the top of the plug is normally positioned below the pressing surface of the pad, thus causing the pad to first engage with and clamp the 100 sole to the shoe throughout its entire area, after which a further pressing movement brings the end of the plug into engagement with the outer sole and presses a portion of the sole into engagement with the insole, as 105 shown clearly in Fig. 2. In order to facilitate the relative movement of the plug and pad and to allow the pad to be compressed

about the plug, the walls of the slot are tapered at 14 and the upper end 15 of the plug is reduced. With this construction, when the rubber pad is compressed it crowds in about the upper and lower ends of the plug, as shown clearly in Fig. 2. It will be observed that the plug 10 engages with the surface of the sole before the complete pressure has been applied and that after 10 this engagement of the plug with the sole a portion of the pressure is transmitted to the unyielding plug. This action substantially prevents the rounding over of the extension edge of the outsole at the heel seat, 15 as with this type of pressing form before the pressure becomes great enough to sink the shoe into the pad the plug 10 takes the pressure and moves the pad block at the heel seat downwardly, equalizing the pressure 20 over the entire shoe sole.

Under various conditions it is desirable to vary the normal position of the end of the plug with relation to the surface of the pad and to this end the plug is provided 25 with a base member 17 and a cap 18 adjustable relative thereto. As will be noted from an inspection of Fig. 1, the base member is provided with a lower portion which fits closely within the recess 12, and a reduced 30 threaded portion 20 which engages with a threaded recess 21 formed in the cap. In order to lock the parts in their adjusted position the threaded portion 20 is provided with a longitudinal slot 22 and a set screw 35 23 is threaded transversely in the cap, the end of the set screw projecting into the slot to prevent a relative rotation of the cap and base member, as shown clearly in Fig. 4.

While it is preferred to employ the specific construction and arrangement of parts 40 shown and described, it will be understood that this construction and arrangement is not essential except so far as specified in the claims, and may be changed or modified 45 without departing from the broader features of the invention.

The invention having been described, what is claimed is:

1. A pressing form having an inner pressing member arranged to bear upon the sole 50 with an unyielding pressure, an outer pressing member surrounding the inner member and bearing upon the sole with a yielding pressure, and means for causing a relative movement of the two members when pressure 55 is applied to the sole to form an indentation in that portion of the sole engaged by the inner member.
2. A pressing form comprising a yielding pad for engaging with the shoe sole, and an 60 unyielding member projecting through the pad and arranged to engage with a restricted area of the outsole to press this portion of the outsole into engagement with the insole during the sole laying operation. 65
3. A pressing form having a supporting base, a yielding pad resting upon the base, and a plug extending through the pad and having its upper end normally positioned beneath the surface of the pad to contact 70 with the sole after the pad has been initially compressed.
4. A pressing form comprising a rubber pad having a slot extending therethrough, and a plug supported in the slot and having 75 a reduced upper end normally positioned beneath the surface of the pad to allow the material of the pad to close around the end of the slot when the pad is under compression. 80
5. A pressing form comprising a support, a rubber pad mounted upon the support, a stud located in the pad and having a base member, a cap portion mounted thereon and adjustable relative to the base member, and 85 means for retaining the cap portion in adjusted position.

HERMAN A. DAVENPORT.
